UNITED STATES PATENT OFFICE.

EDGAR E. PHINNEY, OF NEW YORK, N. Y., ASSIGNOR TO MONROE CALCULATING MACHINE COMPANY, OF NEW YORK, N. Y., A CORPORATION OF NEW YORK.

CARRIAGE-SHIFTING MEANS FOR CALCULATING-MACHINES.

1,330,652.

Specification of Letters Patent.

Patented Feb. 10, 1920.

Application filed March 3, 1917. Serial No. 153,367

To all whom it may concern:

Be it known that I, EDGAR E. PHINNEY, a citizen of the United States, residing at New York, in the county of New York and State 5 of New York, have made a certain new and useful Invention in Carriage-Shifting Means for Calculating-Machines, of which the following is a specification.

Figure 1 is a side view with parts broken 10 away, showing the carriage in lowered position.

Fig. 2 is a section on the line 2—2, Fig. 1.

Fig. 3 is a view similar to Fig. 1, showing the carriage lifted.

15 Fig. 4 is a view similar to Fig. 2 showing the parts in the positions shown in Fig. 3.

The invention has relation to calculating machines having a pivoted carriage, and particularly to improved key-operated means 20 for shifting the carriage endwise or transversely of the machine.

The invention consists in the novel construction and combinations of parts, as hereinafter set forth.

25 In the accompanying drawings, illustrating the invention, the numeral 2 designates the casing of the machine, 4 the carriage and 5 the numeral wheels or dials of the carriage upon which is registered the calculation, 30 said wheels having each an attached gear wheel 5', normally in engagement with underlying gear wheels 11 of the casing, suitable differential actuating or selecting mechanism and carrying mechanism being de- 35 signed for engagement with the wheels 11, as shown in my co-pending application for patent Serial Number 142,190.

The carriage 4 is pivoted upon bearings 79 of the casing, and is provided with means 40 whereby it may be shifted endwise upon said bearings, step by step, to disengage the wheels 5' from the wheels 11 and to re-engage said wheels 5' with others of the wheels 11, for the purpose, mainly, of facilitating the registration of the results in the performance of problems in multiplication and subtraction. During the first half of the shifting movement the carriage is raised pivotally, to clear the dial wheels 5 from the underlying wheels 11, and during the last half of such movement is lowered, to secure the reengagement of the gears.

This means consists of a rotatable rod or shaft 80, mounted in a sleeve 81 of the cas-

ing and bearing at its rear end a double 55 crank arm 82, having diametrically opposite crank members, each member having at its outer end a pin 83, designed to engage any one of a series of open-bottom notches 84 of the carriage frame. The shaft 80 has at its 60 forward end key-operated means for rotating the same, consisting preferably of a mutilated gear wheel 85, loosely mounted thereon and carrying a pivoted spring-pressed pawl 86, said pawl engaging a 65 ratchet wheel 87, fast upon said shaft; a depressible key 88 having a stem 89 provided with rack teeth or notches 90 engaging said gear wheel and turning the same in the depression of the key. The key stem has sliding engagement within a perforation 91 of the top plate of the casing and a perforation 92 of a small horizontal plate 93, spaced apart from said top plate and upheld by a post 94 of horizontal frame plate 95, a screw 70 96 serving to secure the plate 93 to said post and having a washer 96'.

The crank arm 82 is normally horizontal, and in the depression of the key to raise the carriage will be thrown a little past vertical position, the carriage in its fall carrying the crank arm therewith and causing said arm to complete a half turn, the pawl 86 then engaging the diametrically opposite tooth or shoulder of the ratchet wheel and holding the shaft 80 against backward movement. The key is depressed sufficiently to cause a throw of the gear wheel a little more than one-quarter around, for the purpose stated, and said gear wheel and the key are 90 returned to normal position by a coiled spring 97 surrounding the sleeve 81, one end of the spring being fixed to the gear wheel and the other to an upright plate 98 of the casing, by which said sleeve is carried. 95 The return movement of the mutilated gear and of the key is limited by engagement of a stop projection 99 of said gear with the washer 96'.

Another and similar shaft 80' is provided 100 adjacent to the shaft 80, and is provided with duplicate key-operated means for rotating the same in a direction opposite to that in which the shaft 80 is rotated, to accomplish the shifting of the carriage to 105 the left, the first described means being for the purpose of shifting the carriage to the right. This duplicate key-operated means

has the same reference numerals applied thereto as those applied to the first described means, but differentiated by the exponent 1.

The carriage in its fall, during the last 5 half of the shifting movement, will come to rest upon the pins of the oppositely extending crank arms.

I claim:

1. In a calculating machine, a casing having a series of gear wheels, an endwise shiftable pivoted carriage having a series of wheels engaging said gear wheels, and means for raising the carriage pivotally and shifting it endwise including a depressible key, a rotatable shaft, and means for rotating said shaft including an intermittent clutch, one member of which is fast to said shaft and rotatable therewith in the fall of the carriage and the other member of 20 which is operable by the key, and means for returning said other member and the key to normal position.
2. In a calculating machine, a series of gear wheels, an endwise shiftable pivoted carriage having a series of gear wheels engaging the first named wheels, and means for raising the carriage pivotally past the vertical center of its throw to shift it endwise and including a depressible key, a rotatable element operated thereby and means for rotating said element upon actuation of the key including an intermittently acting clutch, one member of which is fast to said element and rotatable therewith in the fall 30 of the carriage and the other member of which is operable by the key, and means for returning said other member and the key to normal position.
3. In a calculating machine, a series of gear wheels, an endwise shiftable pivoted carriage having a series of gear wheels engaging the first named wheels, a depressible key, and means operated by said key for

raising the carriage pivotally past the vertical center of its endwise throw, said means 45 operating to release the key when the carriage is so raised past the vertical center of its throw and adapted to admit of the automatic fall of the carriage to complete its throw through force of gravity. 50

4. In a calculating machine, a series of gear wheels, an endwise shiftable pivoted carriage having a series of gear wheels engaging the first named wheels, and key-operated means for raising the carriage pivotally past the vertical center of its endwise throw, said means adapted to admit of the release of the key when the carriage is raised as stated and to admit of the automatic fall of the carriage and including an 55 intermittently acting clutch, one member of which relates to the key and the other member of which relates to the carriage, and means for returning the key and its related clutch member to normal position. 60 65

5. In a calculating machine, a casing having a series of gear wheels, an endwise shiftable pivoted carriage having a series of registering wheels engaging said gear wheels, and key-operated means for raising 70 the carriage upon its pivot and shifting it endwise, including a rotatable shaft having a ratchet wheel, a gear wheel loosely mounted upon said shaft and carrying a pawl engaging said ratchet wheel, a key 75 stem having a rack engaging said gear wheel, and spring means for returning said gear wheel and said key stem to normal position.

In testimony whereof I affix my signature, in presence of two witnesses.

EDGAR E. PHINNEY.
